Patented Feb. 26, 1901.

J. P. GOMES.

DENTAL PRESS FOR COMPRESSING DENTAL FLASKS.

(Application filed Nov. 26, 1900.)

(No Model.)

UNITED STATES PATENT OFFICE.

JOSEPH P. GOMES, OF BROOKLYN, NEW YORK.

DENTAL PRESS FOR COMPRESSING DENTAL FLASKS.

SPECIFICATION forming part of Letters Patent No. 669,031, dated February 26, 1901.

Application filed November 26, 1900. Serial No. 37,813. (No model.)

To all whom it may concern:

Be it known that I, JOSEPH P. GOMES, a citizen of the United States, residing at New York city, borough of Brooklyn, county of Kings, State of New York, have invented certain new and useful Improvements in Dental Presses for Compressing Dental Flasks, of which the following is a full, clear, and exact description, reference being had to the drawings which accompany and form part of the same.

My invention relates to a press which is designed particularly for the use of practicing dentists and in dental laboratories, in which one or more dental flasks of any description now known and used by the dental profession may be placed and compressed for vulcanizing the substance contained in the flasks. It is constructed in such a way as to be entirely independent of flasks to be compressed by it, is provided with compressing-plates so made that equal pressure is exerted upon the flasks, and all its essential parts are detachable and independent of each other.

Certain minor improvements, which will be hereinafter particularly pointed out, are also covered by my invention.

In the accompanying drawings, Figure 1 shows in elevation a press made in accordance with my invention. Fig. 2 shows a plan of the topmost compressing-plate. Fig. 3 is a section through A B of Fig. 2 and shows details of the two upper compressing-plates. Fig. 4 is a plan showing the two bottom plates, one upon the other, and also showing details of arm attachments to be hereinafter more particularly noted. Fig. 5 is a section through C D of Fig. 4. Figs. 6 and 7 show arms used as hereinafter described.

Similar numerals refer to similar parts throughout the several views.

1 is a wrench having a triangular key at its lower extremity, which easily fits into a socket 10, located in a screw 3.

4 is a circular plate, in the center of which the screw 3 is located. This plate 4 is constructed so that a portion of it, 12, is raised about one-fourth of an inch above the rest of it, and at the extremities of this raised portion 12 are grooves 16, made to accommodate the clamps 13 at the top extremities of the arms 9 or 23. This plate 4 is held in its proper

and relative position by guide-pins 2, which are firmly attached to another plate 5 and which pass through openings 18 in plate 4. 55 Three guide-pins 2, as shown in the drawings, are provided with heads like pin-heads. If desired, they may be made without those heads, and then the plate 4 will be easily detachable from the portion of the press below 60 for purpose of cleaning, &c. The screw 3 is easily detachable from the plate 4 and the wrench 1 is easily detachable from the socket 10 in screw 3.

5 is another circular plate parallel to plate 65 4. At its center it is provided with a slightly-raised portion 19, upon which the screw 3 descends or from which it is released when operating the press. The guide-pins 2 are firmly attached to this plate 5, as heretofore noted. 70 This plate 5 is of sufficient size to entirely cover the top portion of any flask 8 used in dentistry. It is provided with indentations 20 to admit the arms 9 or 23 into their proper position, as will be readily seen by referring 75 to Fig. 1.

6 is another circular plate, also parallel to plates 4 and 5, upon which the flask 8 (any flask) rests when in position to be compressed. Upon the outer edge of this plate, in three 80 places directly beneath the extremities of 12 in plate 4, are slightly-raised portions 15, beneath which grooves are cut, into which hinges 14, at the bottom extremities of the arms 9 or 23, exactly fit. The plate 6 is provided upon 85 its circumference with three circular indentations 22, into which pins projecting upward from plate 7 fit, as will be hereinafter noted.

7 is another circular plate, upon which the press rests when it is to be operated. It is 90 provided with screw-holes 21 and is firmly screwed down upon a table 17. Three pins 11 project upward from it which exactly fit into the indentations 22 of plate 6, as above noted, and by this means rotary motion of 95 the press is prevented while operating it by means of the screw 3 and wrench 1.

9 and 23 are arms by which plates 4 and 6 are held together when the press is in use. Their only difference consists in their length, 100 the shorter to be used when but one flask is to be compressed and the longer when more than one flask is to be compressed at the same time.

The press is operated as follows: Place the hinges 14 of the arms 9 or 23 in their position in the grooves beneath 15 of plate 6 and then place plate 6 upon plate 7, so that 5 the pins 11 of plate 7 fit into the indentures 22 of plate 6. The hinges 14 rest upon the plate 7, and the arms 9 or 23 are held in position, as shown in Fig. 4, by the mere weight of plate 6. Then place any flask 8 upon plate 6. If 10 two flasks are to be compressed at the same time, place one directly upon the other and use either arms 9 or 23, as the case may require. Then upon the flask or flasks place plates 4 and 5, held together by guide-pins, 15 so that the extremities of 12 of plate 4 are directly above 15. Let the screw 3 be sufficiently released and lift arms 9 or 23 upon their hinges until the clamps 13 upon the top extremities of the arms 9 or 23 fit into the 20 grooves 16 of plate 4. Then insert the wrench 1 into socket 10 and turn to right. The screw 3 descends upon 19 of plate 5, and as the screw 3 and plate 5 come in contact plate 4 is lifted away from plate 6 and by means of the tension of arms 9 or 23 pressure is exerted upon 25 plate 5, through which it is directly transmitted to the flask or flasks 8.

It is to be observed that the top portions of all dental flasks 24 consist of plates independent of the remaining portions of the flasks. These plates 24 as now used become warped at their outer edges by reason of unequal pressure exerted upon them, the pressure being confined by any press now in use 30 to the central portion of the plate. As the plate 5 in my press covers the entire top portion of this plate 24 this difficulty, now so common, is obviated.

When the screw 3 comes into contact with 40 19 of plate 5, one quick and sharp turn to the right will cause more than sufficient pressure upon the flasks than is necessary for the purpose in view. The wrench 1 is then removed by simply lifting it out of its socket, and the

entire press, with its flask or flasks, may be 45 lifted away from plate 7 and is then ready to be placed in the vulcanizer.

After the process of vulcanizing is finished the press with flasks contained in it are again placed upon plate 7. Insert the wrench 1 50 into socket 10, turn to left, and the arms 9 or 23 fall away of their own weight into the positions shown in Fig. 4. As at this time the press is very hot the advantage of not having to handle the arms is obvious. The plates 55 4 and 5 are readily removed and the flasks are ready for use. All parts of the press are then readily detachable for cleaning, &c.

I am aware that prior to my invention presses for the use of dentists have been 60 made in which a flask and press together have been combined and in which arms and a wrench have been used in a way similar to the use of the arms and wrench in my invention. I do not therefore claim that the improvements in my press cover such improvements broadly; but 65

What I do claim as my invention, and desire to secure by Letters Patent, is—

1. In a dental press a combination of three 70 parallel plates two of which are held together in their relative positions by means of guide-pins, and the three connected by independent arms provided with clamps and hinges at their extremities substantially as described. 75

2. A dental press provided with three parallel plates, a screw and three connecting-arms all of which are quickly and easily detachable from each other substantially as described. 80

In testimony whereof I have signed my name to this specification, this 21st day of November, 1900, in the presence of two subscribing witnesses.

JOSEPH P. GOMES.
